(57) CLAIM

The ornamental design for a sunshade umbrella stand, as shown and described.

DESCRIPTION

FIG. 1 is a front view of the sunshade umbrella stand showing my new design;

FIG. 2 is a back view thereof;

FIG. 3 is a left side view thereof;

FIG. 4 is a right side view thereof;

FIG. 5 is a top view thereof;

FIG. 6 is a bottom view thereof; and,

FIG. 7 is a perspective view thereof.

The broken lines depict portions of the sunshade umbrella stand that form no part of the claimed design.
